(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof; and,

FIG. 3 is a third image thereof.

The subject matter in this patent includes a process or period in which an image changes into another image. This process or period forms no part of the claimed design.

CERTIFICATE OF CORRECTION

PATENT NO. : D782,507 S
APPLICATION NO. : 29/562171
DATED : March 28, 2017
INVENTOR(S) : Ivan Lam

Page 1 of 4

It is certified that error appears in the above-identified patent and that said Letters Patent is hereby corrected as shown below:

On the Title Page

In the Description section, please reinsert original paragraph:

--The outermost broken lines in the figures show a display screen or portion thereof, and form no part of the claimed design. The other broken lines in the figures show portions of the animated graphical user interface that form no part of the claimed design.--.

In the Drawings

Please replace printed Figures 1-3 with original Figures 1-3 as shown on the attached sheets.

Signed and Sealed this
Eighth Day of May, 2018

Andrei Iancu
Director of the United States Patent and Trademark Office
